UNITED STATES PATENT OFFICE.

KEITH F. ADAMSON, OF FORT BRAGG, NORTH CAROLINA, AND HENRY J. STAMBAUGH, OF TROY, NEW YORK.

AUTOMATIC GUN.

Application filed November 1, 1924. Serial No. 747,764.

(GRANTED UNDER THE ACT OF MARCH 3, 1883; 22 STAT. L. 625.)

The invention described herein may be used by the Government, or any of its officers or employees in prosecution of work for the Government, or by any other person in 5 the United States, without payment to us of any royalty thereon, in accordance with the act of March 3, 1883.

The subject of this invention is an automatic gun, designed for shells of 37 mm. 10 caliber though not restricted thereto.

The purpose of the present invention is to provide an automatic gun of the sliding breech block type, in which extraction takes place during an early stage of recoil and 15 ejecting during a later stage. The rammer is energized during recoil and swung to ramming position, which movement releases the rammer to ram a cartridge directly from the magazine into the cartridge chamber 20 while the gun is still in full recoil, the rammer riding a short distance with the gun in counter-recoil to hold the loaded round in place until the breech block starts to close. The magazine is given partial rotation during 25 counter-recoil to successively bring each round into position to be loaded. A disc for indicating the number of rounds fired from a magazine is associated with the mechanism for actuating the magazine and is rotated in unison therewith. Means controlled by the aforesaid disc prevents firing of the last round from the magazine after said round is fed into the gun so that the gun is ready to go into operation when the magazine is replaced or replenished. 30

To these and other ends, our invention consists in the construction, arrangement, and combination of elements, described hereinafter and pointed out in the claims forming a part of this specification.

A practical embodiment of our invention is illustrated in the accompanying drawings, in which,

Figs. 1 and 1^a are plan views partly in 45 section of the gun in battery;

Figs. 2 and 2^a are similar views of the gun in the full recoil position;

Figs. 3 and 3^a are views in left side elevation, partly in section, of the gun in battery;

Figs. 4 and 4^a are similar views of the gun in full recoil;

Figs. 5 and 5^a are views in right side ele-

vation, partly in section, of the gun in battery;

Figs. 6 and 6^a are similar views of the gun in full recoil;

Fig. 7 is a sectional view taken on the line 7—7 of Fig. 1^a;

Fig. 8 is a sectional view taken on the line 60 8—8 of Fig. 1^a;

Fig. 9 is a rear end view of the gun in battery, partly in section to show the rollers of the rammer and the breech block;

Fig. 10 is a rear end view partly in section of the gun in full recoil;

Fig. 11 is a detailed sectional view of the firing mechanism;

Fig. 12 is a detailed sectional view of the firing cam plunger;

Fig. 13 is a fragmentary sectional view of the mechanism for preventing firing of the last round;

Fig. 14 is a sectional view on line 14—14 of Fig. 13;

Fig. 15 is a detailed view of the leaf spring;

Fig. 16 is a plan view of the rear end of the trigger rod;

Fig. 17 is a sectional view on the line 80 17—17 of Fig. 16;

Fig. 18 is a plan view of the rear end of the firing rod;

Fig. 19 is a sectional view on the line 85 19—19 of Fig. 18;

Fig. 20 is a rear elevation partly in section of the trigger and crank; and

Fig. 21 is a view in side elevation thereof.

Referring to the drawings by numerals of reference:

In carrying out our invention, we provide a cradle 1 (see Fig. 7) having a top plate 2 formed with guide ways 3 for reciprocally mounting a jacket 4 which carries a gun barrel 5.

Secured to the forward end of the cradle is a bridge support 6 (see Figs. 1^a to 6^a and Fig. 7) for stationarily mounting a cylinder 7 in which is disposed a spring 8, adapted to be compressed by a piston having a rod 9 100 coupled to the breech ring of the barrel and constituting means for checking recoil and returning the gun to battery.

The breech end of the barrel is formed with a transverse passage 10^a in which is 105 slidably mounted a breech block 10 movable

in opening from left to right and shown in the closed and open positions respectively, in Figures 8 and 9. For the purpose of operating the breech block and imparting to it a 5 more rapid rectilinear movement than that of the part furnishing the moving force a pinion 11 is provided which is in mesh with a rack 12 on the breech block and also with a fixed rack 13, located in the rear of the 10 passage 10^a. The pinion (see Fig. 9) 11 is mounted on a pin 14, passing through a hollow post 15 which is fixed to a transverse slide 16 in the breech ring. The lower end of the post carries a roller 17 retained in 15 place by a nut and washer 18 attached to the lowermost end of the pin 14. The roller slides in a cam slot 19 (see Figs. 1 and 1^a) in the cradle top plate 2 so that as the gun recoils the slide 16 will be moved to the 20 right, the pinion 11 being constrained to revolve by the fixed rack 13.

The cam slot 19 is so shaped that the gun may recoil approximately two and one-half inches with the breech block in the closed 25 position for the purpose of allowing retraction of the firing pin and also a similar distance with the block fully open for a purpose which will presently appear. After the block has opened a sufficient distance to have 30 an ejection chamber 20 in the block in position to receive the empty cartridge case, extraction of the case begins and is completed during the initial three inch movement of the block. During the final three inch movement of the block the empty case is carried 35 thereby to the right by means of lugs 21 in the block so that during further recoil of the gun (the block having completed its opening movement) the base of the cartridge 40 case will be in position to be struck by an ejector 22 (see Fig. 5) which is carried by the drum or magazine and which projects into the breech block when open through an aperture 23 to cause the empty case to be 45 pushed forward until it drops from the ejection chamber 20 of the breech block.

The mechanism for producing extraction of the empty cartridge case includes an L-shaped extractor 24 (see Figs. 3^a, and 4^a) 50 whose foot terminates in a crescentric lip which is normally engaged in the rim of the loaded cartridge. The extractor is mounted in a guide bracket 25 on the left side of the breech ring and is operatively connected to 55 an extractor slide 26, (see also Figs. 1^a, 3^a, and 5^a) by means of a lever 27, which fulcrums about a pin 28 screwed to the breech ring adjacent the slide and locked against removal in any suitable manner. One end 60 of the lever is adapted to slide in a transverse groove in the front end of the extractor to slide in a transverse groove in the front end of the extractor slide and the other end is received in a forked projection 65 on the extractor. (See Fig. 1^a).

The extractor slide is mounted in a recess in the upper right side of the breech ring and is retained by means of keys 29 on the inside walls of the recess which overlap corresponding keys 30 on the slide (Fig. 6). 70 The under face of the slide is recessed to receive a spring 31 (see Fig. 5^a) confined between the rear end of the slide and the front wall of the slide receiving recess of the breech ring. The slide is moved forwardly 75 against the tension of the spring 31 to cause a resultant rearward motion of the extractor through the instrumentality of a spring pressed plunger 32 mounted in the raised rear end 33 of the slide and working in a cam slot 34 on the upper face of the sliding breech block. The breech ring is provided with an aperture 35 to accommodate the plunger as it is moved back and forth by the cam slot. During initial lateral movement 80 of the breech block the plunger rides idly in the cam slot and does not reach the inclined portion of the slot until the ejection chamber 20 of the block is in position to receive the empty case. Extraction then commences and is completed when the plunger arrives at the foremost end of the inclined portion of the slot in which relative position it is constrained to remain until the lugs 21 during the final movement of the breech block have conveyed the empty case to the 85 right. When the breech block is completely open (the empty case being in position to be ejected) the plunger having arrived at the extreme left end of the cam slot will be 90 free to be moved rearwardly under the influence of the spring 31 thereby restoring the ejector to its seat in the breech of the barrel, while the gun is still in recoil.

During counterrecoil of the barrel and the 105 closing of the breech block, the plunger will ride up the inclined surface of the left terminus of the cam slot and across the top of the block until it reenters the right terminus of the slot where it is again in initial position.

During the recoil movement of the gun in which the extraction of the empty cartridge case is accomplished the loading mechanism mounted on the left side of the gun is energized and released. The loading mechanism consists of a rod 36 (see Figs. 3, 3^a, 4 and 4^a), the front end retained by the bridge support 6 and its rear end secured in the cradle extension 1^a. The forward portion of the rod is reduced and surrounded by a coil spring 37, the free end of the spring confined by the head of a hollow rammer 38 reciprocal on the rod and which is formed with splines 39 (see Figs. 3^a, 4 and 7), at least one of which extends the greater length thereof to serve as a guide as will hereinafter appear.

Secured to the jacket 4 is an annular casting 40 in which is securely held a bushing having splines 41 (see Figs. 4 and 7), which 120

are spaced a short distance from but normally aligned with the splines 39 on the rammer when the gun is in battery, as shown in Figures 3^a and 7.

5 Mounted on the rear end of the rammer 38 is a sleeve 42 having an upstanding rammer arm 43 adapted to engage behind a cartridge to advance it into the gun. The under side of the sleeve is recessed and grooved (Figures 3, 9 and 10) to receive a slide 44 (Fig. 3) the rear end of which carries a roller 45, a retaining pin 46 therefor projecting into a slot 42^a in the sleeve to limit independent reciprocal movement of the slide against 10 a cushioning member, specifically a spring 47 which is provided to yieldingly retard the rammer as it is swung to ramming position on completion of its rearward stroke.

Attached to or formed on the cradle extension 1^a (Figs. 3, 4, 9 and 10) is a rounded plate 48 formed with an endless cam groove (Figs. 1 and 2), which for convenience will be designated the lower groove 49 and the upper groove 50. When the gun is in battery, the roller 45 is positioned at the front end of the lower groove 49 (Fig. 9) the loading arm 43 being in outermost or inoperative position. As the gun recoils the splines on the rammer 38 and the bushing in the casing 20 being in alignment the rammer will be retracted during recoil of the gun to compress the rammer spring 37 and the roller 45 will be moved to the rear in the lower groove 49 until coacting with the grooved cam surface 25 51 it will ride into the upper groove 50. This movement results in rotating the rammer 38 in a clockwise direction (looking from the rear) and swings the loading arm 43 to a position in rear of the next cartridge in 30 the magazine. The rotation of the rammer also releases the engaging splines and permits the rammer to be driven forward by the rammer spring to feed the cartridge into the breech while the gun is still in the full 35 recoil position. It will be understood that the breech ring and breech block are provided respectively with openings 52 and 52' (see Fig. 4^a) to permit insertion of the shell and passage of the rammer arm.

40 It will be noted from Figures 4 and 4^a that when the loading movement is completed the rammer has not yet returned to initial position being restrained by the rammer arm which has been brought to rest by the extractor. On counterrecoil the rammer moves forward with the gun until the roller 45 has reached the limit of its forward movement, the rammer arm serving to hold the loaded round in position until the breech block 45 starts to close. During the continued movement of the gun in counterrecoil the loading arm being at rest and in the operative position will pass through the openings 52 and 52' in the breech block and breech ring.

45 The splines on the rammer and bushing

are maintained in interlocking engagement until the gun has returned to within a short distance of the in battery position and when disengaged the rammer is free to rotate in a counter clockwise direction by reason of the initial torsion placed on the rammer spring in assembly and the roller is returned to its normal position in the forward part of the lower groove 49.

50 Referring to Figures 5, 6 and 7, a cam shaft 53 is journaled in brackets on the right hand side of the cradle to permit passage thereabove of the slide breech block. A sleeve 54 (see Figs. 5^a and 6) mounted on the shaft is retained in an apertured lug 55 on the breech ring so as to be reciprocated on the shaft as the gun moves in recoil and counterrecoil. The sleeve is provided with pins 56 disposed in the grooves of the cam shaft for the purpose of causing the sleeve 54 to be rotated a half turn (clockwise) during recoil. Upon completion of recoil a ratchet wheel 57 on the front end of the sleeve is engaged by a pawl 58 mounted on the lug and serving to lock the sleeve against rotary movement during counterrecoil. Referring to Figure 8 a ratchet wheel 59 (see Figs. 7 and 8) mounted on the front end of the cam shaft is adapted to be held by a pawl 60 on the front bracket for the purpose of preventing rotation of the shaft during recoil of the gun.

55 During counterrecoil, the functions of the ratchets are reversed and the cam shaft is rotated a half turn in a clockwise direction. This rotation is transmitted to a drive shaft 61, located underneath the cam shaft (see Figs. 5^a and 7), by means of a bevel gear 62 on the front of the cam shaft, a pinion 63 and worm 64 on a vertical shaft 65 and a worm wheel 66 on the front end of the drive shaft.

60 The ratio of the gearing is such that a half turn of the cam shaft will produce a one-tenth turn of the drive shaft, this rotation being transmitted in the same ratio to the magazine 67 by means of sprockets 68 and a chain 69, whereby the magazine is intermittently rotated during counterrecoil to successively bring each of the ten rounds in the magazine into exact alignment with the bore of the gun and in position to be fed into the bore by the rammer arm.

65 Rotation of the drive shaft is also transmitted in the same ratio to an indicator disc 70 (Figs. 5 and 6) through bevel gears 71, one of which is yieldingly mounted on the drive shaft and the other connected with the disc and rotatably mounted on an arbor 72 screwed into a trigger housing 73 which is rigid with the cradle.

70 Disposed in the trigger housing 73 are a pair of rods having overlapping ends, the rear trigger rod 74 operatively connected to the upper end of a trigger 75 on a pivot

76 by means of a crank 77, journaled in the cradle for the purpose of retracting the trigger rod as the trigger is pressed. The front firing rod 78 carries on its forward end a lever 79 which with an arm 80 forms a bell crank lever for actuating a pivoted cam plate 81 either to the raised or lower position accordingly as the trigger is pressed or released.

10 The two rods are constrained to be moved in unison by means of a lug 82 on the free end of a leaf spring 83 secured to the trigger rod 74 and normally holding the lug in raised position so that it will engage in a 15 slot 84 in the firing rod 78. The lug is formed with a central upstanding extension 85 which projects through and is free to move in an elongated slot 86, which is a continuation of the slot 84.

20 The indicator disc 70 is provided with a ramp 87 on its under side which is so located in its normal position with the pointer 88 on zero that the extension 85 on the lug 82 will pass to the left of the ramp and 25 will be maintained in the path thereon when the trigger is pressed. When the gun returns to battery after loading the tenth and last round the ramp will have returned to initial position and in so doing will engage 30 the extension 85 to depress the leaf spring and release the lug 82 from engagement with the firing rod. The firing rod is then free to be independently carried forward by a spring 89 surrounding the rod and confined 35 by a nut on the front end of the rod and an annular shoulder in the housing, this forward movement actuating the bell crank lever to lower the cam plate 81 and allow the gun to return to battery without firing the 40 last or tenth round.

The trigger rod is again brought into locking engagement with the firing rod by release of the trigger which is then automatically returned to cocked position through a 45 plunger 90 (Figs. 5 and 6) mounted in the grip 91 and bearing against the lower part of the trigger to rotate the trigger on its axis until the upper part of the trigger is stopped by the rear wall 92 of the pivot slot in the 50 grip. This action results in corresponding forward movement of the trigger rod until the lug 82 on the leaf spring is free to spring up into the slot 84 in the firing rod. When the magazine is replenished or replaced the 55 gun is ready to go into operation by pressing the trigger, the cam plate 81 being elevated thereby to actuate the firing mechanism.

Referring particularly to Figures 2, 10 60 and 11, the firing mechanism which may be of conventional structure, is carried by the breech block 10 and includes a hollow firing pin 93 formed with a striker 94 adapted to project through an opening in the breech 65 block. Within the firing pin is a slidable

tubular member 95 closed at one end to confine a spring 96 in the firing pin and formed with a slot 97 adapted to receive a combined cocking and tripping lever 98 squared on a shaft 99 and inserted into the slot 97 through 70 an aperture 100 in the lower side of the firing pin. The firing pin is held in cocked position by a sear 101, which is raised by its spring to engage in a slot 102 in the firing pin.

75 The outer end of the shaft 99 is provided with an arm 103 adapted to be swung upwardly to rotate the shaft by means of a plunger 104 which in turn is elevated by the cam plate 81. During initial rotation of the shaft the combined lever 98 drives the inner member 95 forward to compress the spring 96 while continued rotation causes a projection 105 on the lever to engage a notch 106 on the sear to depress the sear and release 80 the firing pin.

85 When in fired position, the firing pin will be at rest against the front wall of the firing pin recess in the breech block so that the spring will tend to force the inner member 95 to the rear. However, inasmuch as the cocking lever bears against both the firing pin and the inner member and since the leverage between the inner member and the cocking lever is greater than that between the firing pin and the lever, the resultant force on expansion of the spring will produce rearward movement of both of the members thereby retracting the firing pin to 90 cocked position where it is held by the sear.

95 The plunger 104, which is mounted on one side at the rear end of the breech ring is provided with a roller 107 for contacting the cam plate 81 and also with an ear 108 on its inner side for compressing a spring 109 disposed in the breech ring and adapted to return the plunger to lowered position so that it need not be actuated by the arm 103 and consume energy from the firing pin spring. 100

105 Any suitable device for locking the cocking lever in idle position may be provided, a preferred form as herein shown consisting of a horizontally disposed bolt 110 (Fig. 2) formed with an annular groove for receiving a lug 111 on the shaft 99. As the shaft 99 is rotated the bolt may be freely reciprocated in an aperture 112 in a vertical bolt 113. The bolt 113 is provided with a handle whereby it may be raised and rotated to change the position of its aperture 112 and the handle may be conveniently lodged in a receding slot 115 to hold the vertical bolt in locking position and cut off reciprocation of the bolt 110 and rotation of the shaft 99. 115

120 To fire the gun assuming it to be in battery and loaded the trigger 75 is pressed re-75 tracting the trigger and firing rod 74 and 78 and elevating the cam plate 81 and plunger 104. The consequent rotation of the shaft 99 125

disengages the sear and releases the firing pin 93 to fire the round. The force of recoil causes the barrel to move rearwardly, the breech block 10 remaining closed until 5 the firing pin is returned to cocked position by the firing pin spring 96 and cocking lever 98. The roller 17 travelling in the inclined portion of the cam slot 19 in the top plate 2 operates through the pinion 11 and fixed rack 10 13 to open the breech block with accelerated speed. When the breech block has opened sufficiently, the plunger 32 riding in the breech block cam slot 33 moves the extractor slide forwardly to turn the lever 27 on its 15 pivot and impart a reverse movement to the extractor 24.

Extraction of the empty cartridge case is completed during the initial opening of the breech block, the final movement of the block 20 serving to carry the empty case to the right where it is in position to be expelled by the ejector 22 as the barrel arrives in the position of full recoil. During this interval, the rammer 38 is energized, partially rotated to release it from its connection with the barrel 25 and driven forward to load a new round into the bore while the gun is in the full recoil position. On counterrecoil, the rammer moves forward with the barrel a short distance thus holding the loaded round in position until the breech block starts to close. 30

During recoil, the sleeve 54 on the cam shaft 53 is retracted and rotated to locked position so that it may rotate the cam shaft 35 on counterrecoil. The cam shaft through gearing of suitable ratio actuates the drive shaft 61, which in turn, operates the magazine 67 to bring a live round into alignment with the bore of the barrel.

40 If the trigger has not been released, the cam plate 81 will be in the raised position and as the gun runs into battery the plunger 104 will accordingly be elevated to actuate the firing mechanism. If not desired to sustain firing, the trigger is released and the plunger 90 in the grip and the spring 89 on the firing rod will drive the interlocked trigger and firing rod 74 and 78 forward to lower the cam 81 and allow the gun to return to 45 battery without actuating the firing mechanism.

While in the foregoing there has been illustrated and described such combination and arrangement of elements, as constitute 55 the preferred embodiment of our invention, it is nevertheless desired to emphasize the fact that interpretation of the invention should only be conclusive when made in the light of the subjoined claims.

60 We claim:

1. The combination of a cradle, a gun mounted to recoil and counterrecoil thereon, a sliding breech block, cooperating means on the block, gun, and cradle for opening and 65 closing the block, an extractor operated

through the block to place the empty case in the block and returnable independently when the block is completely open; an ejector insertable through the block during the final stage of recoil to expel the empty case, an 70 independently mounted rammer energized during recoil and adapted to be swung to ramming position, said swinging movement releasing the rammer to load a round while the gun is in full recoil, a cam shaft mounted 75 on the cradle and normally locked against rotation during recoil, means engaging the shaft and movable with the gun for rotating said shaft on counterrecoil, a magazine, a drive shaft operatively connected with the cam shaft for partially rotating the magazine during counterrecoil, an indicator disc driven from said shaft, a housing on the cradle, a pair of overlapping locked rods in 80 said housing, a trigger connected by a crank to the rearmost rod, a cam plate connected by a crank to the foremost rod, said cam plate being normally in lowered or inoperative position and adapted to be elevated when the rods are retracted, means on the 85 disc for releasing the foremost rod for independent forward movement after the last round in the magazine has been loaded, a firing mechanism in the breech block, and means operable through elevation of the cam 90 plate for actuating said mechanism.

2. The combination of a cradle, a gun reciprocally mounted thereon, a sliding breech block, cooperating means on the block, gun, and cradle for opening and closing the block, an extractor operated by the block to place 100 the empty case in the block and returnable independently when the block is completely open, means operable during the final stage of recoil for expelling the empty case, an 105 independently mounted rammer energized during recoil and adapted to be swung to ramming position and released to load a round while the gun is still in full recoil, a magazine on the cradle, means unlocked to 110 set position on recoil for partially rotating said magazine on counterrecoil, a disc driven through said means and adapted to rotate in harmony with the magazine, a firing mechanism in the breech block, a trigger 115 mechanism for controlling said firing mechanism, and means associated with the disc for temporarily rendering the trigger mechanism inoperative after the last round from the magazine has been loaded into the gun. 120

3. The combination of a cradle, a gun reciprocally mounted thereon, a sliding breech block, cooperating means on the block, gun, and cradle for opening and closing the block, means for extracting the empty case from the gun during an early stage of recoil, means for ejecting the case during a later stage, means energized during recoil for loading a new round into the gun while 125 the gun is still in full recoil, means for posi- 130

tioning a new round in line with the bore during counterrecoil, a firing mechanism in the breech block, a trigger mechanism for controlling said firing mechanism, and 5 means for automatically rendering the trigger mechanism temporarily inoperative after loading the last round from a magazine.

4. The combination of a cradle, a gun reciprocally mounted thereon, a rod stationarily supported on the cradle, a rammer and rammer spring surrounding the rod, said rammer provided with splines at least one of which extends the greater length of the 10 rammer, an annular splined member fixed to the gun and adapted on recoil to retract the rammer, a rammer arm on the rear of the rammer and normally in inoperative position, a slide mounted on the under side of the 15 arm, a roller, a pin for retaining the roller on the slide and for limiting independent movement of the slide, a rounded plate on the cradle, said plate having an endless cam groove for the roller, means for yieldingly 20 retarding the rammer as the roller reaches the end of its rearward stroke and rides into the uppermost portion of the cam groove, said movement of the roller serving to swing the rammer arm to ramming position and 25 to disengage the rammer from the annular member on the gun whereby to load a round while the gun is still in full recoil.

5. The combination of a cradle, a gun reciprocally mounted thereon, a rod stationarily supported on the cradle, a rammer and a rammer spring surrounding the rod, said rammer provided with splines, means on the gun for retracting the rammer during recoil, a rammer arm on the rammer and normally 30 in outward or inoperative position, a roller mounted at the rear of the rammer, a rounded plate on the cradle, said plate having an endless cam groove for the roller, means for yieldingly 35 retarding the rammer as the roller reaches the end of its rearward stroke and rides into the uppermost portion of the cam groove, said movement of the roller serving to swing the rammer arm to ramming position and to disengage the rammer 40 from its connection with the gun whereby to load a round while the gun is still in full recoil.

6. The combination of a cradle, a gun reciprocally mounted thereon, a rammer and rammer spring mounted on the cradle, means 45 on the gun for retracting the rammer during recoil, a rammer arm normally in inoperative position, cooperating means between the cradle and rammer and movable with the rammer for simultaneously swinging said rammer to ramming position and releasing it from its connection with the gun for immediate return movement whereby to load a 50 round while the gun is still in full recoil, and means for yieldingly retarding the ram-

mer as it reaches the end of its rearward stroke.

7. The combination of a cradle, a gun reciprocally mounted thereon, a rammer and rammer spring mounted on the cradle, means 70 on the gun for retracting the rammer during recoil, a rammer arm normally in inoperative position, cooperating means between the cradle and rammer and movable with the rammer for simultaneously swinging said 75 rammer to ramming position and releasing it from its connection with the gun for immediate return movement whereby to load a round while the gun is still in full recoil.

8. The combination of a cradle, a gun reciprocally mounted thereon, a rammer and rammer spring mounted on the cradle, means 80 on the gun for retracting the rammer during recoil, a rammer arm normally in inoperative position, cooperating means between the cradle and rammer for swinging the rammer to ramming position at the end of 85 its rearward stroke and for releasing it for immediate return movement whereby to load a round while the gun is still in full recoil.

9. The combination of a cradle, a gun reciprocally mounted thereon, a sliding breech block adapted to open and close during the intermediate stages of recoil and counterrecoil, and a rammer adapted to be energized on recoil of the gun and to return independently to load a round while the gun is still in full recoil, said rammer being further adapted to complete its return movement during the initial stage of counterrecoil so as to hold the loaded round in position until the breech block starts to close.

10. The combination of a cradle, a gun reciprocally mounted thereon, a rammer and rammer spring recoilable with the gun, and 105 means for moving the rammer to ramming position and releasing it for independent return movement while the gun is still in full recoil.

11. A cradle, a gun reciprocally mounted 110 thereon, round loading mechanism energized by the gun and means for releasing said round loading mechanism to load a round into the gun while the gun is in full recoil.

12. The combination of a cradle, a gun reciprocally mounted thereon, a sliding breech block having a chamber, cooperating means on the block, gun, and cradle for opening and closing the block, an extractor 115 and an extractor slide mounted on the gun, a lever connecting the extractor and the slide and fulcrumed adjacent the slide, a vertical plunger on the rear end of the slide, said breech block formed with an irregular 120 cam slot on its upper face for receiving an end of the plunger, the plunger adapted to be moved forwardly during an intermediate stage in the opening of the block and retained in forward position until the block 125 is completely open, said plunger then being

free to be returned to initial position to seat the extractor, means on the block for causing the extracted case to be moved laterally therewith, and means operable during recoil of the gun for ejecting the case from the block.

13. The combination of a cradle, a gun reciprocally mounted thereon, a sliding breech block having a chamber, cooperating means on the block, gun, and cradle for opening and closing the block, an extractor and extractor slide mounted on the gun, a lever connecting the extractor and the slide and fulcrumed adjacent the slide, cooperating means on the slide and block for retracting the extractor during an intermediate stage in the opening of the block, said means being free to restore the extractor to its seat when the block is completely open, means on the block for picking up the empty case when extracted and conveying it to one side of the gun, and a stationary ejector adapted to project through the block as the gun recoils for expelling the case.

14. The combination of a cradle, a gun reciprocally mounted thereon, a sliding breech block having a chamber, cooperating means on the block, gun, and cradle for opening and closing the block, an extractor and extractor slide mounted on the gun, a lever connecting the extractor and the slide and fulcrumed adjacent the slide, cooperating means on the slide and block for retracting the extractor during an intermediate stage in the opening of the block, said means being free to restore the extractor to its seat when the block is completely open, and means for ejecting the extracted case.

15. The combination of a cradle, a gun reciprocally mounted thereon, a sliding breech block having a chamber, cooperating means on the block, gun, and cradle for opening and closing the block, means controlled by the block for extracting the empty case into the chamber, lugs on the block for picking up the empty case and conveying it to one side of the gun during final movement of the block, and a stationary ejector adapted to project through the block as the gun recoils for expelling the case.

16. The combination of a cradle, a gun reciprocally mounted thereon, a sliding breech block, cooperating means on the block, gun, and cradle for opening and closing the block, means controlled by the block for extracting the empty case, and means operable during recoil of the gun for ejecting the case.

17. The combination of a cradle, a gun reciprocally mounted thereon, a cam shaft carried by the cradle, a ratchet for locking said shaft against rotation during recoil, a member movable with the gun and slideable on the shaft, a ratchet for locking said member against rotation on counterrecoil whereby to partially rotate the shaft, a drive shaft, re-

duction gearing connecting the shafts, a magazine, sprockets on the drive shaft and magazine, and a chain on said sprockets whereby the magazine may be intermittently rotated.

18. The combination of a cradle, a gun reciprocally mounted thereon, a cam shaft carried by the cradle, a member movable with the gun and slideable on said shaft, means for alternately locking said shaft and member against rotation on recoil and counterrecoil whereby to partially rotate the cam shaft on counterrecoil, a drive shaft operatively connected with the cam shaft, a magazine, sprockets on the drive shaft and the magazine, and a chain on said sprockets whereby the magazine may be intermittently rotated.

19. The combination of a cradle, a gun reciprocally mounted thereon, a cam shaft carried by the cradle, means movable with the gun for partially rotating the cam shaft on counterrecoil, a magazine in rear of the gun, and means operatively connecting the shaft and magazine for intermittently rotating said magazine.

20. The combination of a cradle, a gun reciprocally mounted thereon, a magazine on the cradle, means for intermittently rotating said magazine on counterrecoil, an indicator disc operatively connected with said means and adapted to be rotated in harmony with the magazine, a housing on the cradle, a pair of overlapping slotted rods in said housing, a leaf spring carried by the rearmost rod, a lug on the free end of the spring, a central extension on the lug, said lug normally held in raised position to lock the rods for unitary movement, a trigger connected by a crank to the rearmost rod, a cam plate connected by a crank to the foremost rod, said cam plate being normally in lowered or inoperative position and adapted to be elevated by retraction of the rods, and a ramp on the disc adapted when the last round in the magazine has been loaded to depress the extension on the lug whereby to release the foremost rod for independent movement, and means for automatically restoring the rods in interlocked relation.

21. The combination of a cradle, a gun reciprocally mounted thereon, a magazine on the cradle, means for intermittently rotating said magazine during counterrecoil, an indicator disc operatively connected with said means and adapted to be rotated in harmony with the magazine, a housing on the cradle, a pair of overlapping rods in said housing a trigger connected by a crank to the rearmost rod, a cam plate connected by a crank to the foremost rod, said cam plate being normally in lowered or inoperative position and adapted to be elevated by retraction of the rods, and means on the disc for releasing the foremost rod for independent forward

- movement after the last round in the magazine has been loaded.
22. The combination of a cradle, a gun reciprocally mounted thereon, a magazine on the cradle, means for intermittently rotating said magazine, an indicator disc operatively connected with said means and adapted to be rotated in harmony with the magazine, a housing on the cradle, a pair of overlapping normally locked rods in said housing, a trigger connected to the rearmost rod, a cam plate connected to the foremost rod, said cam plate being normally in lowered or inoperative position and adapted to be elevated by retraction of the rods, and means associated with the disc for automatically releasing the foremost rod for independent forward movement at predetermined intervals.
23. The combination of a cradle, a gun reciprocally mounted thereon, a magazine on the cradle, means for intermittently rotating said magazine, a pair of normally locked rods carried by the cradle, a trigger connected to the rearmost rod, a cam plate connected to the foremost rod, said cam plate being normally in lowered or inoperative position and adapted to be elevated by retraction of the rods, and means rotatable in harmony with the magazine for releasing the foremost rod for independent forward movement after the last round in the magazine has been loaded.
24. The combination of a cradle, a gun reciprocally mounted thereon, a magazine on the cradle, means for intermittently rotating said magazine, a pair of normally locked rods carried by the cradle, a trigger connected to the rearmost rod, a cam plate connected to the foremost rod, said cam plate being normally in lowered or inoperative position and adapted to be elevated by retraction of the rods, and means controllable by rotation of the magazine for disconnecting the rods to temporarily restore the cam plate to inoperative position after the last round in the magazine has been loaded.
25. The combination of a cradle, a gun reciprocally mounted thereon, a sliding breech block in the gun, a firing mechanism in the breech block, a shaft connected with said mechanism and projecting beyond the block, a trigger rod carried by the cradle, a trigger and a cam plate, cranks for connecting the rod to the trigger and cam plate whereby the cam plate may be elevated as the rod is retracted, and a plunger mounted on the gun and adapted to be raised by the cam plate to rotate the shaft.
26. The combination of a cradle, a gun reciprocally mounted thereon, a sliding breech block in the gun, a firing mechanism in the block, a shaft connected with said mechanism and projecting beyond the block, a cam plate pivoted to the cradle, a trigger mechanism for raising and lowering said cam plate, and a plunger mounted on the gun and adapted to be raised by the cam plate to rotate the shaft.
27. The combination of a cradle having a cam slot, a gun reciprocally mounted thereon, a sliding breech block in the gun, a rack on said block, a fixed rack on the gun at the rear of the breech block recess, a transverse slide underneath the block, an upright post fixed to the slide, a pinion mounted on the upper end of the post and meshing with the racks, and a roller on the lower end of the post disposed in the cam slot of the cradle.
28. The combination of a cradle, a gun reciprocally mounted thereon, a transversely sliding breech block, and cooperating means on the block, gun, and cradle for opening and closing the block during movement of the gun at a rate more rapid than the part supplying the motive force.
29. In a gun, a sliding breech block having a chamber, and means for extracting an empty case into said chamber.
30. The combination of a cradle, a gun reciprocally mounted thereon, a transversely sliding breech block, and means for opening and closing the block during movement of the gun at a rate more rapid than the part supplying the motive force.
